(57) **CLAIM**

The ornamental design for a fire pit as shown and described.

DESCRIPTION

FIG. 1 is a perspective view of the fire pit in an open state with the cover removed;

FIG. 2 is a perspective view of the fire pit in a closed state;

FIG. 3 is a top plan view of the fire pit in an open state;

FIG. 4 is a bottom plan view;

FIG. 5 is a side elevation view from any of the four sides; and,

FIG. 6 is a top plan view of the cover in isolation.

The broken line shown in the drawings are for the purpose of illustrating portions of the fire pit and form no part of the claimed design.
